UNITED STATES PATENT OFFICE.

ALEXANDER BOYNTON, OF SAN ANTONIO, TEXAS.

STAGE-LIFT FLOWING DEVICE.

Application filed December 10, 1926. Serial No. 153,948.

This invention relates to stage lift flowing devices especially adapted for use in oil and other wells.

The invention forming the subject matter 5 of this application is intended to provide for the admission of compressed gas or air to a well tubing at a point below the level of the oil therein and to utilize the expansion of the compressed gas or air in lifting 10 the fluid in the tubing to the surface.

A further aim is to provide for the introduction of the compressed air or gas into the column of oil in such a manner that lifting units or slugs may be formed promptly upon 15 the admission of the compressed air or gas into the tubing.

Another aim of the invention is to provide an induction valve having simple means by which settling mud or the like in the 20 tubing is prevented from lodging at the air or gas admission point and interfering with the proper functioning of the valve.

A still further aim of the invention is to provide an induction valve for stage lift 25 flowing devices which is of highly simplified construction, reliable in operation, and comparatively cheap to manufacture.

Other objects and advantages will be apparent during the course of the following 30 description.

In the accompanying drawings forming a part of this application and in which like numerals are employed to designate like parts throughout the same,

Figure 1 is a side elevation of an automatic valve.

Figures 2 and 2^A are sectional views illustrating a tubing positioned within the casing of a well and equipped with induction 40 valves embodied in the invention.

Figure 3 is a sectional view through one of the induction valves.

In the drawing, the numeral 5 designates a casing which, as illustrated in Figure 1, 45 has the upper portion thereof provided with a casing head 6 by which the liberation of gas which accumulates in the casing is prevented. Figure 1 illustrates in a general way an automatic control valve by means of 50 which the flowing of the well by a compressed fluid such as air or gas is terminated when the level of the fluid in the tubing drops below a predetermined point.

Figure 2 illustrates that the tubing 8 has 55 a number of induction valves 9 incorporated therein for the admission of a lifting agent

such as compressed air or gas from the well equipped with the invention or from any other well. In case air is employed a compressor is, of course, necessary.

A suitable number of lengths of pipe may be attached to the lower end of the tubing to form a settling or sediment receiving chamber 10. Mud or other heavy sediment may settle into the chamber 10 and thereby 65 be prevented from interfering with the free movement of the oil and the compressed lifting agent up through the tubing. The sediment chamber 10 may be of any suitable diameter and the lower end of the same is 70 closed by a cap 11. When the tubing is withdrawn for any purpose the cap 11 may be detached for removing the sediment within in the chamber 10.

Each inlet or induction valve 9 has a flow 75 passage 12 of the same diameter and cross-sectional formation as the bore of the tubing to provide an even passage for the alternate slugs of oil and compressed lifting fluid. It might be added at this point that the successful operation of the invention is dependent in a measure at least on the provision of smooth passages for the alternate slugs of lifting and lifted fluids. The lifting fluid is, of course, previously compressed 80 gas or air introduced into the tubing by way of the induction valves and if a body of the lifting fluid is broken up during its movement through the tubing its ability to further elevate the oil is immediately destroyed. 85 The result will be the descent of a slug of oil formerly sustained and elevated by the lifting fluid, be it gas or air.

In the above connection it is noted that the continuation 14 of the tubing has a very 90 gradually bent elbow 15 to aid in conducting the flow to the desired point. The very gradual curvature of the elbow 15 offers little resistance and obstruction to the flow 95 of the fluid as will be appreciated.

Returning to a consideration of Figure 3 it will be seen that each induction valve 9 has a valve chamber 17 in communication therewith whereby the lifting medium such as compressed gas or air may be introduced into 100 the tubing from the casing. More specifically the longitudinally extending valve chamber 17 has an inlet tube and valve seat 20 threaded therein and having the upper end thereof formed with a seat 22 for engagement by a tapered valve head 24 on the lower end of a spiral valve body 26.

The spiral body 26 is provided at the upper end thereof with a tapered valve head 28 adapted for contact with the seat 30 of an outlet tube and valve seat 32. When the head 28 is engaged with the seat 30 the admission of additional lifting fluid such as compressed air or gas to the tubing by way of a particular induction valve is prevented. The admission of a compressed lifting fluid to the tubing by way of a particular valve is possible only when the head of oil in the tubing above that valve is sufficient to prevent the rapid inrush of air into the tubing. In more specifically explaining this feature of the invention it is pointed out that when the level of fluid drops below a particular valve there is nothing of consequence to resist the free and rapid movement of the compressed lifting fluid into the tubing and during such inrush of the compressed lifting fluid, the spiral body will be raised to move the head 28 into sealing engagement with the seat 30. Therefore, it will be seen that the free inrush of air through a particular passage 17 is only momentary. The compressed lifting fluid supplied by way of the member 32 enters an annular supply chamber 34 in the flared lower portion of the section 36 of the induction valve. Figure 3 clearly illustrates that the upper section 36 is provided with a depending flange 38 which defines the inner wall of the annular chamber 34 and which is spaced from the upper end of the body of the induction valve a sufficient distance to cooperate with the same in the formation of an annular jet by which air is admitted to the tubing about the entire periphery of the column of oil in the tubing.

The arrangement of the annular jet by which the compressed lifting fluid is supplied to the tubing permits of the admission of sufficient lifting fluid to the tubing in a comparatively short interval to permit of the formation of what might be said to be a complete lifting unit. In other words, almost immediately upon the admission of a predetermined volume of a compressed lifting agent to the tubing, the same becomes effective as an oil flowing medium.

The above represents an important advantage over stage lift flowing devices which supply a compressed lifting agent to the tubing from a single point so that the various bubbles of lifting agent must unite in their upward movement before they can become effective as a lifting medium. The admission of a compressed lifting agent from a single point may also be objectionable to some users on the ground that cutting of the oil will result.

Further consideration of Figure 3 will clearly show that the depending flange 38 in addition to defining one wall or side of the annular jet also acts as a protecting medium for the member 32. Mud sediment or the

like settling in the tubing can not lodge on the nozzle since the flange 38 is spaced a substantial distance in from the same. Also the lower edge of the flange 38 is beveled inwardly as shown at 40. Before mud, sediment or the like can accumulate in sufficient quantity to interfere with the normal functioning of the induction valve, gravity will assert itself and the mud, sediment et cetera, will move down into the sediment chamber. In this connection gravity will be assisted by the inrushing air from the chamber 34.

The manufacture of an induction valve as shown in Figure 3 is greatly simplified by making the same in two sections which are threaded as illustrated. The threading of opposite ends of the valve chamber 17 for the members 20 and 32 is a very simple matter since this may be accomplished before the two sections of the induction valves are connected.

The lower portion of the induction valve may be cored out as indicated at 41 to provide a convenient starting place to either drill or ream the valve chamber. The extended upper portion of the member 32 may be hexagonal or otherwise shaped for engagement by a wrench.

In the installation of the improved stage lift flowing device one of the valves for the compressed lifting fluid may be placed approximately 450 feet from the surface and from 450 feet down to about 1050 feet one valve may be placed at every 120 feet. From 1050 feet to 1450 feet the valves may be approximately 100 feet apart.

From 1450 feet to 1690 feet the valves may advantageously be 80 feet apart and below 1690 feet the valves may be placed approximately 60 feet from each other.

Below the inlet valves for the lifting agent a check valve 140 may be located to retain in the tubing the oil that may not have been blown out in the flowing process. It is important to note that when the valve heads 24 are seated the same cooperate with the check valve 140 in retaining oil in the tubing. Necessarily some oil will settle back after a well has flowed, unless an unnecessary amount of gas is wasted to perfectly clean the tubing. There is no reason why the oil should be allowed to settle back into the well exteriorly of the tubing and build up a back pressure against the oil seeking to come into the well. For that reason the check valve 140 is employed. Furthermore, oil which is allowed to flow back into the well exteriorly of the tubing not only wastes energy, but also results in agitation which assists in liberating the lighter properties of crude oil. Therefore the check valve prevents unnecessary back pressure on the sands, avoids agitation and loss of energy.

The oil enters the tubing by way of inlets

51. As the level of the oil in the tubing is about 300 feet above the level of the oil in the casing several valves will be exposed to permit of the admission of compressed air or gas to the tubing at a point below the level of the oil therein.

The highly compressed lifting agent or fluid which enters by way of the passage 17 does not expand until it enters the tubing

10 and rises somewhat and it is this expansion and consequent pressure which is relied on to bring the oil to the surface. The compressed lifting agent during its passage thru the valve chamber 17 partakes of no appreciable expansion. This is true because of the 15 resistance resulting from the presence of a higher column of oil in the tubing than in the casing. In other words expansion of the lifting agent is resisted by the head of oil 20 in the tubing, but such expansion does, however, take place after the lifting fluid enters the tubing.

When the level of oil in the tubing drops below a particular valve, the free inrush of 25 air or gas by way of the passage 17 will result in the expansion of the air or gas while still in the passage 17 with the result that the spiral body 26 will be moved from a slightly elevated position to a completely 30 elevated position to close the member 32 and thereby cut off the further supply of air to the tubing by way of that valve. In other words, so long as the level of fluid is above a particular valve, the valve body 26 will 35 rise only slightly under the influence of the compressed fluid and when the fluid drops below a particular inlet valve the valve head 28 is immediately seated to cut off the admission of additional compressed air or gas 40 by way of that valve.

The spiral body 26 has a free working fit within the passage 17, but the valve heads 24 and 28 are somewhat less in diameter than the diameter of the passage 17 to allow 45 of the free passage of air or gas into the tubing. The contact of the compressed fluid with the spiral body will cause the spiral body to rapidly rotate with the result that the valve seats at opposite ends of the 50 chamber 17 and the valve heads are kept ground in at all times. Sufficient sand is present in the well to supply the necessary grinding compound.

Every movement of compressed air or gas 55 however small through the valve chamber 17 rotates the spiral body 26 since there is no friction between the valve head 28 and its seat. Every contact of the valve heads with their respective seats is necessarily a rotating contact and this results in maintaining the valves properly seated until completely worn out. The spiral body 26 is heavy enough to avoid the danger of sticking and the centrifugal force resulting from the 60 rapid turning of the valve keeps the spiral

body and the attached valve heads clean. Herein resides one of the advantages of a spiral valve body over a ball valve. Centrifugal force tends to clean a ball valve only partially both poles of the axis of a 70 ball being comparatively stationary and, therefore, not ground at such points. For this reason a ball valve soon wears into something of an elliptical form and unfit for completely effecting a good seal.

In operation a highly compressed lifting fluid is introduced into the casing and should it be that the oil within the tubing extends to within four or five hundred feet of the surface the uppermost valve may be 80 relied on to admit sufficient compressed fluid to blow the oil above the same to the surface.

As the level of oil drops additional valves 85 come into play and the rapid rush of air or gas through a particular valve chamber 17, due to the drop in the level of oil in the tubing, will result in the movement of the valve head 28 to closed position to render that valve inoperative for the present. This action, however, never occurs until the fluid level in the well has been lowered to a point where at least the next valve is exposed. Compressed air or gas then enters at the 90 lowermost exposed valve until the oil above 95 that valve has been blown out through the tubing. The next valve below has then become exposed by the drop of the level of the fluid within the casing exteriorly of the tubing and that valve will come into play.

This process will continue until the level 100 of the fluid outside of the tubing has been lowered to the level of the perforations 51. When the perforations 51 are exposed, the well, of course, is pumped off and the pressure of the air or gas will be quickly relieved through these perforations. When the pressure of the air or gas is thus rapidly decreased the automatic valve illustrated in Figure 1 will terminate the flowing operation. It will be observed that there is a passage 60 establishing communication between the casing and the automatic control valve.

By way of example, it might be pointed out that if there are 200 pounds of air or gas in the casing and 50 pounds of back pressure in the tubing there will be 150 pounds of air or gas capable of lifting 500 feet of oil at 30 pounds to the hundred feet. Therefore, if the valves are spaced approximately 100 feet apart below the level of the oil within the tubing five valves may be exposed and all of these valves would be closed except the lower one or two because the back pressure there would not admit air or gas 115 fast enough to close the lower valves, but would admit enough highly compressed air or gas to flow the oil from the tubing above. In other words, the fluid having the lifting force may enter the tubing only at points 120 125 130

where substantial heads of oil are encountered.

Compressed air or gas entering through a particular valve has less volume than it assumes after it has risen appreciably in the tubing and the expansion of the air or gas after it enters the tubing is relied on to lift the head of fluid.

With 100 pounds of effective pressure, that is, exclusive of back pressure in the casing, and the level of the oil in the tubing is 300 feet above the level of the oil in the casing, several valves in the tubing will be exposed to the admission of air or gas below the surface of the oil in the tubing and the compressed air or gas would enter by way of the exposed valves and expand below slugs of oil, which expansion and consequent lifting is accelerated as the air or gas approaches the surface.

Having thus described the invention, what is claimed is:

1. An induction valve for well pumps comprising a cylindrical body having a pair of sections, one of which has a depending flange and a flared portion cooperating in the formation of an annular chamber, there being means whereby said flared portion and the other section may be detachably connected, the other of said sections having a valve chamber, inlet and outlet valve seats detachably secured in the ends of the valve

chamber and having fluid passages, and a valve between said seats.

2. An induction valve for well pumps comprising a hollow body having a pair of sections, one of which has a depending flange and a flared portion cooperating in the formation of an annular chamber, there being means whereby said flared portion and the other section may be detachably connected, the other of said sections having a valve chamber, inlet and outlet valve seats detachably secured in the valve chamber and having fluid passages, and a valve between said seats, the outlet valve seat being provided with a nozzle extending into the annular chamber to a point beyond the plane of the free edge of said flange.

3. An induction valve for well pumps comprising a body having a pair of sections arranged end to end and having communicating bores forming a passage for the products of a well, one of the sections being formed with an annular chamber encircling said passage and communicating therewith, the other section being formed with a valve chamber communicating with said annular chamber, and a valve in said valve chamber, said valve chamber being provided with a nozzle extending into said annular chamber.

In testimony whereof I affix my signature.

ALEXANDER BOYNTON.
